UNITED STATES PATENT OFFICE

2,483,590

BENCH TYPE HONING MACHINE

Wallace F. Mitchell, Chicago, Ill., assignor to
Ammo Tools, Inc., a corporation of Illinois

Application December 5, 1945, Serial No. 632,908

12 Claims. (Cl. 51—72)

1

The invention relates to so-called bench type honing machines. While it may be utilized with hones of various sizes, the structure illustrated is particularly adapted for the driving and feeding of small bore hones.

One of the objects of the invention is to provide an improved device of this character which is substantially foolproof in operation and will operate the hone with a maximum degree of efficiency.

Another object of the invention is to provide a device of the character above described which is of very simple construction, embodies a minimum number of parts, occupies only a very small space, and may be manufactured and sold cheaply, and one which is sufficiently strong and durable to give efficient service over a long period of time.

A further object is to provide a bench type honing machine which may be readily and easily operated and adjusted for the honing operation without the necessity of using skilled labor.

Another object of the invention is the provision of a housing which not only encloses the operating mechanism but also provides storage for the parts of the hone such as the mandrels and stones.

Another very important object is to provide a honing machine having instant starting and stopping operation. This is highly important from the standpoint of stopping because it eliminates marring of the finished product by the hone. It is highly desirable that in a device of this kind there be no coasting of the tool after the honing operation is completed to prevent marring of the hone surface with its subsequent disadvantages.

A further object of the invention is to provide an automatically engageable friction clutch for connecting the power drive mechanism to rotate the hone, a manually controlled lever for controlling said clutch and stone feed mechanism also connected to said lever for feeding the stones radially outwardly to the desired extent after the clutch has been engaged, said feed mechanism having adjusting means to determine the extent of outward movement of the stones.

The invention further consists in the several features hereinafter set forth and more particularly defined by claims at the conclusion hereof.

In the drawings:

Figure 1 is a front elevation view of a honing machine embodying the invention, the operating treadle being omitted and parts being broken away;

Fig. 2 is a side elevation view of the machine shown in Fig. 1;

Fig. 3 is a vertical sectional view taken along the line 3—3 of Fig. 1;

Fig. 4 is a vertical sectional view taken along the line 4—4 of Fig. 3;

2

Fig. 5 is a detailed vertical sectional view along the line 5—5 of Fig. 3;

Fig. 6 is a horizontal sectional view taken along the line 6—6 of Fig. 4;

Fig. 7 is a vertical sectional view taken along the line 7—7 of Fig. 6.

The machine embodying the invention is designed to take any suitable hone 10 (Fig. 2) which usually includes a mandrel 11 and stones 12 with means, usually wedge connections, between a reciprocating member and the stones for moving the stones radially outwardly to the desired amount to produce the finished bore in the part to be honed. As the particular form of the hone constitutes no part of the present invention, further description of the hone is not deemed necessary, but for one form of expansible hone that may be used on this machine reference may be had to my copending application Serial No. 615,165, filed September 8, 1945 now Patent No. 2,445,277, dated July 13, 1948 for "Hone." The machine herein provides the power for rotating the hone and for controlling and moving the wedge operating member of the hone.

The machine includes a housing 13 (Fig. 1) having a base 14, and front, back and cover plate portions 16, 17, and 18 bolted thereto. The sides of the housing are provided with doors 19 (Figs. 4 and 6) suitably hinged, as by gravity type hinges, to the front and back plates, which doors are provided with shelves 20 forming storage compartments for the parts of the hone such as the mandrels and stones, the mandrels being carried on one of the doors and the stones on the other door. The housing 13 is designed to completely enclose all the operating mechanism.

The hone 10 is carried by a hollow shaft 21 (Fig. 3) in which a hone expanding member 22 is slidably mounted. Shaft 21 has a head portion 23 secured by a set screw 24 to a drive adapter 25.

The drive adapter 25 (Fig. 3) is secured by a threaded connection 26 to a hollow hone drive spindle 27 in which a feed operating and control rod 28 is freely and slidably mounted and normally urged toward the left, as viewed in Fig. 3, by a spring 29 interposed between a shoulder 30 on the spindle 27 and a head member 31 provided with a reduced outer end 32 having a bearing race therein. The spindle 27 is journalled in spaced bearings 33 in a supporting housing 34 secured at its front end in the front plate 16 and is prevented from lengthwise movement by the rear shoulder of the adapter 25 engaging the front end of said housing 34 and a collar 35 locked by screw 36 to the spindle and engaging the rear end portion of the housing 34.

For driving the spindle 27, a drive pulley 37 is mounted for free rotation thereon and is adapted to be connected thereto by a friction

clutch. Drive pulley 37 is connected by a V-belt 38 with a pulley 39 on the drive shaft 40 of an electric motor 41 whose circuit connections with a power supply line are controlled by a switch 42 mounted on the front plate 16 and having an operating handle 43 which is readily accessible to the operator standing in front of the machine. For mounting the motor 41 in the housing and maintaining the proper tension in the belt 38, the base of the motor is mounted on a saddle 44 (Fig. 4) pivotally mounted on a horizontally disposed shaft 45 fixed to the back plate 17. Saddle 44, at a point offset from its pivotal mounting, engages a tensioning screw 46 adjustably mounted in the housing 13 and secured by a lock nut 47. With this construction the pulley 37 is continuously driven by the motor 41.

The friction clutch for connecting the pulley 37 with the spindle 27 includes friction elements 48 (Fig. 3) of leather or other suitable material secured to the faces of the hub of said pulley, one of which is engageable with a collar 49 fixed to the spindle 27 and the other of which is engaged by a shiftable clutch sleeve or member 50 slidably mounted on the spindle 27 but drivingly connected thereto by a keyed connection 51 therewith. The member 50 is constantly urged into clutching connection with the pulley 37 by a spring 52 interposed between member 50 and the spindle collar 35. The shifting of the member 50 is under the control of the operator through a treadle operated lever 53 operatively connected at one end with member 50 (Figs. 4 to 7, inclusive) and at its other end with a pedal operated link 54 (the pedal not being shown). The lever 53 is normally held in its upper position by a tension spring 55 (Fig. 3) whose loading is greater than that of the spring 52, so that the spring 52 cannot function to shift the member 50 to clutch engaging position until the operator by a downward movement of the treadle and lever 53 nullifies or counteracts the tension of the spring 55. This same movement of the lever 53 is used for moving the feed rod 28 to expand the hone and is accomplished, as follows:

The support 34 for the spindle 27 has bifurcations 56 (Figs. 5 and 6) apertured to receive pivot pins 57 in the form of socket head screws secured to a lever head member 58 which is secured to the lever 53 by bolts 59. On opposite sides of the pivot pin 57 and radially offset therefrom there are sets of pivots 60 and 61 formed by pin extensions of the bolts 59 and other bolts 62. One set 60 of these pivots is disposed in a plane passing through the axis of the spindle 27 and carries a half collar 63 (Figs. 3 and 5) mounted in an annular groove 64 in the clutch member 50 and held thereagainst in clutch throw out position by the lever spring 55. The other set 61 of the pivots is mounted in the lower end of a T-shaped member 65 (Figs. 3, 4 and 5) whose upper end has a bore 66 to receive a settable feed regulating shaft or rod 67 (Figs. 3, 6 and 7) and is secured against lengthwise movement relative thereto by collars 68 clamped to said shaft. The shaft 67 is adjustably mounted in an overarm member 69 having a rearward depending arm portion 70 carrying a radial thrust bearing 71 whose inner race engages the outer end ball race end 72 of rod 28. Downward movement of the lever 53 moves the collar 63 rearwardly and out of con-

tact with the member 50 to allow spring 52 to engage the clutch to drivingly connect the pulley 37 with the spindle 27 and at the same time moves the member 65, shaft 67, and arm 69 forwardly or toward the right and thus moves the rod 28 against the pressure of the spring 29 to expand the hone. Varying the position of rod 67 and consequently the position of the member 65 relative to the arm 69 will, therefore, vary the stroke of the rod 28 and consequently the radial movement of the stones.

In order to position the stones 12 of the hone 10 in operating contact with work having different sizes of bores and vary the stroke of rod 28 and hence the amount of radial outward movement of the stones 12, the shaft 67 which extends through bosses 72 in the member 69 has a threaded portion 73 in threaded engagement with the front boss 72 and has a cylindrical shank portion 74 slidably mounted in and carrying a pin 75 extending through diametrically disposed slots 76 in the sleeve portion 77 of a settable member 78 whose shank 79 extends through a bearing 80 in the front plate 16 and has a suitably indexed adjusting dial 81 (Figs. 1 to 3, inclusive) secured to its outer end by a screw 82 and provided with a hand wheel or knob 83. The main divisions of the scale markings 84 on the dial may be graduated to read in ten-thousandths and the other divisions in fractional parts of ten-thousandths and are adapted to cooperate with a fixed indicator point 85 on the front plate. Turning the dial 81 will, through the slidable but non-rotatable connection between the member 78 and shaft 67, turn this shaft to move the arm 69 to the left or the right and hence determines the amount of longitudinal movement that may be imparted to the rod 28 on the downward movement of the lever 53 which in its lower position engages a fixed stop 86 formed by the lower end of the slot 85 in the front plate 16.

With the above construction, depression of the lever 53 throws in the drive clutch, and at the same time, through the parts above described moves the feed rod 28 toward the right to expand the stones an amount predetermined by the adjustment of the stroke of said rod through the adjustment of the feed regulating shaft 67, but in addition for the initial setting of the stones and for any desired further small movement of the stones after the pedal is depressed, the operator by turning the knob 83 to the right may through the connections described move the feed rod 28 further to the right to expand the stones to bring the bore to the desired diameter.

In operation the hone 10 is first attached to the drive adapter 25, and in doing this the rod 28 is operatively engaged with the wedge operating member 22, so that upon moving of the rod 28 to the right the stones will be moved radially outwardly. At this time the motor switch 42 is in the off position. To adjust the tool for the honing of a bore of a particular size, the foot pedal and in turn the lever 53 connected thereto is fully depressed until the latter engages the bottom of the slot 85 in the front plate 16 which serves as a foot pedal stop 86a. The knob 83 is then rotated to the right to move the overarm 69 and in turn the hone adjusting rod 28 and the member 22 to the right to bring the stones 12 to a position where they firmly engage the wall of the bore in the work to be honed. The foot pedal and lever 53 is then released, and having determined approximately at

least the amount of material to be ground from the bore in the honing operation, the knob 83 is further turned to the right to move the arm 69 and shaft 28 further to the right to an extent corresponding to the amount of material to be removed. Thereafter with the pedal in a released position and the hone positioned in the bore, the machine is started by throwing in the switch 42 and the lever 53 is depressed. A slight depression of the foot pedal throws in the clutch and causes the stones to rotate and at the same time engages the stones with the bore and the honing operation begins.

Continued pressure on the foot pedal will tend to constantly expand the stones to the full limit of the adjustment made until the lever 53 strikes its stop 86a at which time the honing operation has been carried out to the extent of the adjustment made less, of course, the wear of the stones which may be compensated for by observation and additional adjustment through a slight movement of the knob 83 by the operator. With this arrangement after having determined the amount of adjustment necessary to remove a given amount of material in respect to the first piece of work operated upon, substantially the proper adjustment may be made in subsequent operations, so that subsequent pieces of work may be honed with the single adjustment of the tool.

There may be times when the operator will find it desirable to adjust the extent of expansion of the hone during operation. In that case he may do so while the machine is running and while the lever 53 is depressed by rotating the knob 83 to the desired extent.

It will be noted from the foregoing that the stop 86a formed by the bottom of the slot 36 in which the lever 53 moves serves as a definite stop or limiting means for the end of adjustment under all adjustment conditions. The initial adjustment is set when the lever 53 is in depressed position, and that being the case, the range of adjustment from beginning to end of the honing operation is determined by the extent of depression of the lever 53 as governed by the depth of the slot 86.

I desire it to be understood that this invention is not to be limited to any particular form or arrangement of parts except insofar as such limitations are included in the claims.

I claim:

1. In a honing machine adapted for supporting and operating an expansible hone, the combination with a rotatable hone drive spindle, of a drive member normally mounted for free rotation thereon, an automatically engageable clutch for drivingly connecting said member with said spindle, a reciprocatory feed rod for expanding the hone, means including a feed adjusting member for moving said feed rod to expand the hone, and an operator controlled means operatively connected to said clutch and said feed rod moving means and adapted in its inoperative position to hold said clutch disengaged.

2. In a honing machine adapted for supporting and operating an expansible hone, the combination with a rotatable hone drive spindle, of a drive member normally mounted for free rotation thereon, an automatically engageable clutch for drivingly connecting said member with said spindle, a spring retracted feed rod adapted for expanding the hone, means including a feed adjusting member for moving said feed rod to expand the hone, and means including a lever operatively connected to said clutch and said

feed rod moving means and adapted in its inoperative position to hold said clutch disengaged.

3. In a honing machine adapted for supporting and operating an expansible hone, the combination with a rotatable hone drive spindle, of a drive member normally mounted for free rotation thereon, a friction clutch for drivingly connecting said member with said spindle, yieldable means urging said clutch into driving engagement, a reciprocatory feed rod for expanding the hone, means including a feed adjusting member for moving said feed rod to expand the hone, an operator controlled lever normally retracted and operatively connected to said clutch to disengage the same and normally hold it disengaged, yieldable means for holding said lever normally retracted, said lever being operable upon movement thereof from its retracted position to engage said clutch and also being operatively connected to said feed rod moving means to move the same to expand the hone when said clutch is engaged.

4. In a honing machine adapted for supporting and operating an expansible hone, the combination with a rotatable hone drive spindle, of a drive member mounted thereon for rotation relative thereto, an automatically engageable clutch for drivingly connecting said member with said spindle, a reciprocatory feed rod for expanding the hone, an overarm in thrust engagement with said rod to move the same to expand the hone, a manually settable feed adjusting member having a threaded connection with said overarm, and a clutch control member connected to said adjusting member to move the latter and in turn said overarm when said control member is actuated to engage said clutch.

5. In a honing machine adapted for supporting and operating an expansible hone, the combination with a rotatable hone drive spindle, of a drive member, an automatically engageable clutch for drivingly connecting said drive member with said spindle for rotating the latter, a spring retracted reciprocatory feed rod for expanding the hone, an overarm in thrust engagement with said rod to move the same to expand the hone, a feed adjusting member having a threaded connection with said overarm, an operator controlled spring retracted lever, a releaseable connection between said lever and clutch to hold said clutch in disengaged position when said lever is retracted, and a connection between said lever and said feed adjusting member to move the same on release of the connection between said lever and clutch.

6. In a honing machine adapted for supporting and operating an expansible hone, the combination of a housing, a rotatable hollow hone drive spindle extending into said housing, a journal support for said spindle mounted in said housing, a drive pulley mounted on said spindle for free rotation relative thereto, a friction clutch for connecting said pulley with said spindle including a shiftable clutch member, a spring interposed between said clutch member and said journal support, a lever having a head portion pivotally mounted on said journal support and having a member pivotally connected thereto and engageable with said shiftable clutch member, means for tensioning said lever to overcome the tension of said first named spring to hold the shiftable clutch member in a released position, a reciprocatory feed rod extending through the hollow of said drive spindle for expanding the hone, a spring for 75 moving said rod to a retracted position, an over-

arm in thrust engagement with said rod to move the same against the pressure of said spring to expand the hone, a feed adjusting shaft having a threaded connection with said overarm, a member pivotally connected to the head member of said lever and secured to said feed adjusting member whereby said overarm operates to move said feed rod when and after said lever is moved to permit said first named spring to engage said clutch.

7. In a machine of the character described, an expandible and contractible tool for sizing bores, a rotatable spindle for supporting and driving said tool, means for controlling the expansion and contraction of said tool, drive means normally disconnected from said spindle, means shiftable along said spindle for connecting said drive means with said spindle to rotate the latter and said tool, and operator-controlled means for simultaneously actuating said shiftable means and said control means to cause said drive means to rotate said spindle and tool and to expand said tool, respectively, said operator-controlled means having a lost-motion connection with said shiftable means providing for further actuation of said control means independently of said shiftable means after connection of said drive means with said spindle.

8. In a machine adapted for supporting and operating an expandible tool for sizing bores, a rotatable tool drive spindle, a drive member for said spindle mounted for rotation normally independently of said spindle, a clutch having a predetermined maximum driving effort when fully engaged operative to drivingly connect said drive member with said spindle, means for expanding the tool, and operator-controlled means operatively connected to said clutch and to said tool expanding means, respectively, for simultaneously effecting engagement of said clutch and actuating said expanding means to expand said tool and operative to expand the tool beyond the extent of expansion thereof effected when said operator-controlled means is actuated to effect full engagement of said clutch.

9. In a machine adapted for supporting and operating an expandible tool for sizing bores, a rotatable tool drive spindle, a drive member for said spindle mounted for rotation normally independently of said spindle, a clutch mounted on said spindle and operative for drivingly connecting said drive member with said spindle, said clutch having a predetermined maximum driving effort when fully engaged, means for expanding the tool, clutch actuating means including a member shiftable along said spindle for effecting engagement of said clutch, operator-controlled means operatively connected to said clutch actuating means and to said tool expanding means, respectively, for simultaneously effecting engagement of said clutch and actuating said expanding means to expand the tool, and operative to expand the tool beyond the extent of expansion thereof effected when said operator-controlled means is actuated to effect full engagement of said clutch, and means normally maintaining said operator-controlled means in inoperative position with said tool expanding means inoperative and said clutch disengaged.

10. In a machine adapted for supporting and operating an expandible tool for sizing bores, a rotatable tool drive spindle, a drive member for said spindle mounted for rotation normally independently of said spindle, a clutch operative

when engaged for drivingly connecting said drive member with said spindle, a spring urging said clutch into engaged condition, a reciprocatory feed device for expanding the tool, a spring urging said feed device into retracted position, means including a feed adjusting member for advancing said feed device to expand the tool, a clutch actuating member for effecting engagement of said clutch, operator-controlled means operatively connected to said clutch actuating member and to said feed adjusting member, respectively, for simultaneously effecting engagement of said clutch and advancing said feed device to expand said hone, and a spring stronger than said first spring and yieldingly urging said operator-controlled means into inoperative position with said feed device retracted and said clutch disengaged.

11. In a machine adapted for supporting and operating an expandible tool for sizing bores, a rotatable tool drive spindle, a drive member for said spindle mounted for rotation normally independently of said spindle, a clutch for drivingly connecting said drive member with said spindle, a reciprocatory feed member for expanding the tool, means including a reciprocatory feed adjusting member and a thrust member carried rigidly thereby for translational movement therewith and in thrust engagement with said feed member for advancing said feed member to expand the tool, a clutch actuating member for effecting engagement of said clutch, and operator-controlled means operatively connected to said clutch actuating member and to said feed adjusting member, respectively, for simultaneously effecting engagement of said clutch and advancing said feed member.

12. A machine of the character described comprising an expandible and contractible tool for sizing bores, a rotatable spindle supporting and driving said tool, means for expanding and contracting said tool while said spindle is rotating which includes a tool expanding device passing along said spindle and connected with said tool, an adjustable expansion control element shiftable in a plane parallel with the axis of said spindle, and an element connecting said expanding device with said shiftable expansion control element and translatable in a path parallel with the axis of said spindle, drive means normally disconnected from said spindle, means shiftable along said spindle for connecting said drive means with said spindle to rotate the latter, and operator-controlled means for simultaneously shifting said expansion control element and said shiftable means for actuating said tool expanding and contracting means and said drive-connecting means to cause said expanding and contracting means to expand said tool and said spindle to be driven rotatably, respectively.

WALLACE F. MITCHELL.
